UNITED STATES PATENT OFFICE.

FREDERICK GRETSCH, OF BROOKLYN, NEW YORK.

REED HOLDER.

Application filed March 22, 1926. Serial No. 96,619.

This invention relates to a holder for reeds and particularly to an improved holder especially designed for saxophone reeds and has for an object to provide a construction 5 wherein the reeds are protected when carried in a pocket or when not in use.

Another object of the invention is to provide a reed holder wherein a comparatively stiff structure is provided with flexible 10 means for holding the reeds against the stiff structure and in that way not only support and protect the reeds but hold the same against accidental injury by twisting or bending. 15 A still further object, more specifically, is to provide a holder for saxophone reeds wherein a series of pockets are provided arranged in pairs and associated together in such a manner that the flat sides of opposite 20 reeds will be juxtaposed and thereby assist in maintaining the flexible part of the reeds in correct position.

In the accompanying drawing—

Figure 1 is a perspective view of a holder, 25 disclosing an embodiment of the invention.

Figure 2 is a view similar to Figure 1 but with the binding strap loosened and the covering lid or section open.

Figure 3 is a view similar to Figure 2 but 30 showing the reed carrying structure swung to an outer position.

Figure 4 is a sectional view through Figure 1, approximately on line 4—4.

Figure 5 is an enlarged sectional view 35 through Figure 2, approximately on line 5—5.

Referring to the accompanying drawing by numerals, 1 indicates what may be termed a body which is made from stiff material, as 40 for instance, a stiff piece of leather or imitation leather and connected to this body is a member 2 which may be cloth, leather or other material, said member 2 being folded upon itself so that the member will straddle body 1 as illustrated in Figure 4. This member is secured to body 1 by lines of stitching 3, 4, 5 and 6 whereby there are provided pockets 7, 8 and 9 on each side of the body 1 (Figure 5). It is, of course, evident that 45 two pieces of leather or other material could be stitched in place to make the pockets 7 to 9 inclusive but preferably one piece is used as it may be readily bent around the inner end of body 1 as shown in Figure 4

and thereby provide a better protection for 55 the flexible ends of the various reeds.

When the material 2 is first stitched in place, it lies flatwise against the body 1 but when the various reeds 10 are inserted, they will stretch to a certain extent the material 60 2 and thereby cause the material to substantially contact with the reed for the full length of the insertion and in that way snugly hold the reed against the body 1 which is comparatively thick and stiff. By 65 providing pockets on each side of the body 1, the two reeds in any set of pockets will reinforce each other and assist the body 1 and associated parts in preventing accidental bending of the reeds and, consequently, accidental injury. 70

In order to afford additional protection to all parts of the reed and to make a desirable container or package, a cover 11 is provided having a body section 12 and a reed section 75 13. A portion 14 of the body section 12 is secured to the member 2 adjacent the point that it overlaps the body 1. An elastic or other strap 15 is secured to section 12 by adhesive or otherwise and the overlapped 80 ends 16 thereof are covered with a covering or finishing strip 17.

When the device is in use and it is desired to remove one or more of the reeds, the parts are moved to substantially the position 85 shown in Figure 3. After the reed has been removed, body 1 and associated parts are folded back to the position shown in Figure 2 and then the reed 13 swung downwardly and finally the retaining strap 15 90 applied as shown in Figure 1. The holder may then be placed in the pocket or stored wherever desired and the reeds remaining therein held against injury but ready for quick removal whenever desired. 95

What I claim is:

1. A saxophone reed holder comprising a body formed from a piece of stiff material, a flexible member mounted on said body and extending from near the center thereof down 100 to and over one end and back to near the center at the opposite side, a series of lines of stitching for securing said member to the body so as to divide the member into a series of pockets, the pockets on one side 105 of the body being in line with the pockets on the opposite side, each pocket being adapted to receive a reed with the flat side contact-

2
ing with the body whereby the reeds in the various pockets will reinforce each other, and a covering structure for covering said body, the means forming the pockets and the 5 reeds, said covering structure protecting the exposed ends of said reeds and reinforcing said body for its full length.

2. A holder for saxophone reeds comprising a comparatively stiff body, means presenting a flexible sheet arranged with a portion 10 on each side of the body, each portion extending from one end of the body toward the opposite end, a series of stitching extending through both of said flexible portions 15 and the body for dividing both of the flexible portions so that in connection with the body a series of tapering pockets will be provided on each side of the body, the pockets being arranged in pairs so that when reeds

are placed in the pockets the reeds on opposite sides of the body will act as stiffening means for each other. 20

3. A saxophone reed holder comprising a body formed from a piece of stiff material, a flexible member mounted on said body and 25 extending from near the center thereof to and over one end and back to near the center of the opposite side, and a series of lines of stitching securing said flexible member to the body so as to divide the flexible member into a series of pockets, the pockets on one side of the body being in line with the 30 pockets on the opposite side, each pocket being adapted to receive a reed with the flat side contacting with the body whereby the reeds in the various pockets will reinforce each other. 35
